(57) **CLAIM**

The ornamental design for a car with surface ornamentation, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a first embodiment of the car with surface ornamentation showing my design;
FIG. 2 is a rear perspective view thereof;
FIG. 3 is a front view thereof;
FIG. 4 is a rear view thereof;
FIG. 5 is a right-side view thereof;
FIG. 6 is a top plan view thereof;
FIG. 7 is a bottom view thereof;
FIG. 8 is a front perspective view of a second embodiment of the car with surface ornamentation showing my design;
FIG. 9 is a rear perspective view thereof;
FIG. 10 is a front view thereof;
FIG. 11 is a rear view thereof;
FIG. 12 is a right-side view thereof;
FIG. 13 is a top plan view thereof; and,
FIG. 14 is a bottom view thereof.

1 Claim, 14 Drawing Sheets
